RIVET CARRIER FOR RIVETING MACHINES

Arden L. Johnson, Jackson, Mich., assignor to
Tomkins-Johnson Company, Jackson, Mich., a
corporation of Michigan

Application January 6, 1941, Serial No. 373,293

6 Claims. (Cl. 218—2)

The present invention relates to riveting machines and more particularly to a carrier for transferring rivets from a source to an upstanding anvil.

In Patent No. 2,163,440, to H. A. Tomkins, there is disclosed a riveting machine wherein upsettable members are fed from a chute to a carriage and are transferred by the carriage to an upstanding anvil. The present invention constitutes an improvement over the structure of the foregoing patent and relates particularly to details of an improved rivet transferring structure. The embodiment of the invention disclosed is adapted for clinch nuts. However, it will be understood that the invention may be employed for use with any upsettable member.

Accordingly, an object of the invention is to provide an improved carrier for upsettable members for machines of the character described.

Another object of the invention is to provide a novel structure for holding upsettable members on the rivet transferring carriage.

Still another object of the invention is to provide an efficient structure for maintaining upsettable members in place on the carriage prior to traversing movement of the carriage.

Still another object is to provide a transferring ram having a recess therein for yieldably supporting the rivet carrier.

These and other objects residing in the arrangement, combination and construction of the parts will be apparent from the following specification when taken with the accompanying drawing, in which:

Fig. 1 is a partial vertical section disclosing the invention in association with the anvil of a riveting machine;

Fig. 2 is a section on the line II—II of Fig. 1;

Fig. 3 is a section on the line III—III of Fig. 2;

Fig. 4 is a section on the line IV—IV of Fig. 2, and

Fig. 5 is a section on the line V—V of Fig. 3.

Referring particularly to the drawing, the reference character 1 indicates a frame to which is suitably secured a housing 2. The housing 2 is provided with an internal slide way 3 in which is slidably disposed a transferring ram 4 for reciprocation in a direction from left to right, as disclosed in Fig. 1. The ram 4 has secured to the bottom thereof by screws 5 a plate 6. The plate 6 slides directly on the top of a base portion 7 of the frame 1 and the plate 6 slides beneath angle plates 8 between which the ram 4 is guided during reciprocation, the angle plates 8 being secured to the sides of the base portion 7.

The ram 4 is reciprocated by a rod 9 suitably connected to some reciprocating mechanism such as a pneumatic cylinder and piston, not shown. The rod 9 is slidably disposed in a bore 10 in the

ram 4 and is provided with a head 11 disposed in a recess 12, also in the ram 4 and extending from the inner end of the bore 10. Secured to the rod 9 on a portion thereof and spaced from the ram 4 is a collar 13, and disposed about the portion of the rod 9 between the ram 4 and the collar 13 is a spring 14. The spring 14 is for the purpose of providing a resilient driving connection between the rod 9 and the ram 4 so that should the ram 4 meet with any interference in its movement to the left as viewed in Fig. 1, the resiliency of the spring 14 will prevent any damage from occurring.

The ram 4 is provided with an integral upstanding ram portion 20 in which is provided a longitudinally extending slot 21. The slot 21 has disposed therein one end of a carrier 22. The carrier 22 is provided with a longitudinal bore 23 in which is disposed a rod 24. The rod 24 also extends through the upstanding ram portion 20 and has secured to the outer end thereof lock nuts 25. Disposed about the rod 24 in the recess 21 and bearing against the inner end of the recess 21 and the carrier 22 is a spring 26, the spring 26 tending to resiliently urge the carrier 22 outwardly of the recess 21 but permitting inward movement of the carrier 22 with respect to the upstanding ram portion 20.

The upstanding ram portion 20 is provided with a nose 27 which bears directly on the top of the carrier 22 so that as the carrier 22 moves relatively to the ram 4, the nose 27 slides relatively over the carrier 22.

The carrier 22 is for receiving on the top thereof upsettable members to be transferred from a suitable source such as a chute 28 to an upstanding anvil 29, at which point work is disposed over each upsettable member as it is placed on the anvil and upset. Upsettable members are fed to the chute 28 from a hopper, not shown, in any conventional manner and slide down the chute 28 by gravity. The upsettable members disclosed in the drawing for the purpose of illustrating the invention are clinch nuts, although it will be understood that other upsettable members may be employed. The lowermost clinch nut slides onto the carrier 22 and is stopped on the carrier 22 by a stop 29. The stop 29 is in the form of a rod slidably disposed in a bore 30 in the housing 2 and in the bore 31 in the frame 1. As shown particularly in Fig. 4, the operative face 32 of the stop 29 is inclined inwardly with respect to the clinch nut receiving surface of the carrier 22 to assist in preventing accidental removal of each clinch nut as it is deposited on the carrier 22. With the parts in the position shown in the drawing, it will be evident that the weight of the clinch nuts in the chute 28 will hold the clinch nuts on the carrier against the surface

32 of the stop 29. The stop 29 is adjustable to permit the correct positioning of it each time the type of upsettable member fed to the carrier 22 is changed, so that regardless of the size of the upsettable member being fed down the chute 28, the upsettable member on the carrier 22 will be properly positioned thereon. For fixing the adjustment of the stop 29, a set screw 33 is provided.

When the ram 4 is ready to move to the left as viewed in Fig. 1, the inclined face 32 of the stop 29 together with the weight of the clinch nuts in the chute 28 bearing against the clinch nut on the carrier 22 will tend to maintain the clinch nut on the carrier 22 in its position. However, as soon as the ram 4 starts to move, the nose 27 will engage with the clinch nut on the carrier 22 to move it out of engagement with the face 32 and the clinch nut in the chute 28 at the side of the carrier 22.

In order to prevent the clinch nuts in the chute 28 from moving out of the chute 28 during the traversing of the ram 4, there is provided a plunger 37 disposed in a bore 38 in the housing 2. The plunger 37 has a flat side 39 which is in the face of an inside wall 40 against which the upstanding ram portion 20 slides, as shown particularly in Figs. 4 and 5. Between the inner end of the bore 38 and the plunger 37, as shown in Fig. 3, is a spring 41 for resiliently urging the plunger 37 outwardly against the last clinch nut in the chute 28. Thus, the column of clinch nuts in the chute 28 is maintained against sliding therefrom after the ram 4 and carrier 22 have moved outwardly from the housing 2. The last clinch nut in the housing 2 is released to permit it to slide onto the carrier 22 upon the return of the ram 4 and the carrier 22 by the action of a shoulder 42 on the upstanding ram portion 20 engaging with a shoulder 43 on the plunger 37. The shoulders 42 and 43 are so positioned as to move the plunger 37 to the right as viewed in Fig. 3 and back in Fig. 4, just far enough to clear the clinch nut at the bottom of the chute 28 so that the weight of the clinch nuts above it in the chute 28 will force it onto the carrier 22 and against the surface 32 of the stop 29. The shoulder 43 consists of a projecting segment of the plunger 37 and normally rides in a slot 44 of segmental cross section in the upstanding ram portion 20. Rotation of the plunger 37 in the bore 38 is prevented by the shoulder 43 extending into the slot 44.

For the purpose of maintaining the clinch nuts fed to the carrier 22 thereon during movement of the carrier 22, there is provided a finger 45 pivoted to the upstanding ram portion 20. The pivot consists of an elongated boss 46 having a face of hemicylindrical form disposed in an elongated arcuate recess 47 extending across the top of the upstanding ram portion 20. The boss 46 is provided intermediate the ends thereof with a slot 48 into which projects a pin 49 disposed in a bore 50 in the bottom of the recess 47. The pin 49 maintains the finger 45 against lateral movement in the recess 47. The finger 45 is pivoted about its pivot point by a spring 51 secured in a bore 52 in the finger 45 and in a bore 53 in the upstanding ram portion 20. The nose portion 54 of the finger 45 is maintained in an elevated position as shown in Fig. 1, when the ram 4 is within the housing 2 for receiving a clinch nut on the carrier 22 by means of a tail piece 55 bearing against a camming surface 56 in the

housing 2. The camming surface 56 is inclined so that as the ram 4 and with it the finger 45 move from the housing 2, the spring 51 can draw the nose piece 54 on the finger 45 down onto the clinch nut on the carrier 22 to maintain it in position while the ram is traversed toward the anvil 29.

In operation as soon as a clinch nut has been disposed on the carrier 22 following the upsetting of a clinch nut on the work at the anvil 29, the ram 4 is moved to the left as viewed in Fig. 1 by the action of the rod 9, actuated by some suitable moving mechanism not shown. As the ram and carrier 22 move forwardly, the plunger 37 is released by the forward movement of the shoulder 42 moving away from the shoulder 43 to permit the plunger 37 to engage with the lowest clinch nut in the chute 28. At the same time the tail piece 55 of the finger 45 moves along the camming surface 56 in the housing 2 to permit the nose 54 of the finger 45 to be drawn onto the clinch nut on the carrier 22 by the spring 51. When the ram 4 reaches a position adjacent the anvil 29', the carrier 22 abuts against the anvil 29', but due to the resiliency of the spring 26, the carrier 22 slides into the recess 21, while the ram 4 continues to move forwardly. This relative forward movement of the ram 4 causes the nose 27 of the upstanding ram portion 20 to slide the clinch nut on the carrier 22 from the carrier 22 into a recess 51 on the top of the anvil 29. The ram 4 is then withdrawn into its position within the housing 2 as shown in Fig. 1 where the camming surface 56 engaging with the tail piece 55 cams the nose 54 of the finger 45 upwardly to permit the passage of a clinch nut from the chute 28 onto the carrier 22. At the same time, the shoulder 42 of the upstanding ram portion 20 engages with the shoulder 43 of the plunger 37 to move the plunger 37 backwardly to release the lowermost clinch nut in the chute 28 so that the weight of the clinch nuts above it in the chute 28 may force it onto the carrier 22 to repeat the cycle of operation. While the ram 4 is in its rearward position, work is disposed over the clinch nut on the anvil 29 so that the clinch nut may be upset on the work in a known manner by conventional upsetting structure not shown.

Having thus described my invention, what I desire to secure by Letters Patent and claim is:

1. A rivet carrier for transferring upsettable members fed thereto from a source to an anvil, comprising a carriage for receiving thereon one upsettable member at a time, a ram for transferring the upsettable member on said carriage to said anvil, means to traverse said ram and carriage toward said anvil, means for yieldably maintaining said carriage and ram in a predetermined relation but permitting said ram to be moved relatively to said carriage upon the engagement of said carriage with an abutment during traversing to transfer from said carriage to the anvil the upsettable member thereon, said ram having an internal recess therein in which said carriage is slidably reciprocable, and means for yieldably holding each upsettable member on said carriage as it is fed thereto.

2. A rivet carrier for transferring upsettable members fed thereto from a source to an anvil, comprising a carriage for receiving thereon one upsettable member at a time, a ram having a nose for transferring the upsettable member on said carriage to said anvil, means to traverse said ram and carriage toward said anvil, means

for yieldably maintaining said carriage and ram in a predetermined relation for permitting said ram to be moved relatively to said carriage upon the engagement of said carriage with an abutment during traversing to transfer from said carriage to the anvil the upsettable member thereon, said ram having an internal recess therein, said carriage being movable relatively to said ram in said recess, and means for yieldably holding each upsettable member on said carriage as it is fed thereto.

3. A rivet carrier for transferring upsettable members fed thereto from a source to an anvil, comprising a carriage, means at one side of said carriage for resiliently urging a column of upsettable members directly onto said carriage, a stop at the opposite side of said carriage for stopping the first upsettable member in said column on said carriage and the second upsettable member in said column at the first named side of said carriage, means for resiliently holding on said carriage the upsettable member fed thereto, a ram, means to traverse said ram and carriage toward said anvil and to return the same therefrom, means for yieldably maintaining said carriage and ram in a predetermined relation for permitting said ram to move relatively to said carriage upon the engagement of said carriage with an abutment during traversing to transfer from said carriage to the anvil the upsettable member thereon, a plunger reciprocal in said housing extending in the direction of movement of said carriage and resiliently urged into holding relation with said second upsettable member to maintain the same in its position at the side of said carriage during transferring movement of said ram and carriage, means for maintaining said means for resiliently holding upsettable members on said carriage during the feeding of upsettable members onto said carriage, and an operative connection between said plunger and said ram for moving said plunger out of engagement with the upsettable member against which it abuts to permit the said upsettable member to move onto said carriage, said last named means being operative upon the return of said ram to starting position.

4. A rivet carrier for transferring upsettable members fed thereto from a source to an anvil, comprising a carriage, a chute terminating at one side of said carriage supporting therein a column of upsettable members for gravity feeding the upsettable members therein one at a time directly onto said carriage, a stop at the opposite side of said carriage for stopping the lowest upsettable member in said column on said carriage and the next lowest upsettable member at the first named side of said carriage, means for resiliently holding on said carriage the upsettable member fed thereto, a ram, means to traverse said ram and carriage toward said anvil and to return the same therefrom, means for yieldably maintaining said carriage and ram in a predetermined relation for permitting said ram to move relatively to said carriage upon the engagement of said carriage with an abutment during traversing, to transfer from said carriage to the anvil the upsettable member thereon, a plunger reciprocal in said housing extending in the direction of movement of said carriage and resiliently urged into holding relation with said next to the lowest upsettable

member to maintain the same in its position at the side of said carriage during transferring movement of said ram and carriage, means for maintaining said means for resiliently holding upsettable members on said carriage out of operative association with said carriage during the feeding of upsettable members onto said carriage, a shoulder on said ram, and a shoulder on said plunger, said shoulder on said plunger being in the path of movement of the shoulder on said ram for moving said plunger with said ram when said ram moves to its starting position for moving said plunger out of engagement with the upsettable member against which it abuts to permit said upsettable member to move onto said carriage.

5. A rivet carrier for transferring upsettable members fed thereto from a source to an anvil, comprising a carriage, means to feed upsettable members, one at a time, to said carriage, an axially positionable and slidable member comprising an adjustable stop at one side of said carriage for positioning upsettable members as they are fed onto said carriage, said stop having a substantially flat face inclined to each direction of movement of said upsettable member for limiting movement of each upsettable member as it is fed onto said carriage, and for restraining movement of each upsettable member against said stop from movement from said carriage, a ram for transferring each upsettable member on said carriage to the anvil, means to traverse said ram and carriage toward the anvil and to return the same therefrom, yieldable means for maintaining said carriage and ram in a predetermined relation for permitting said ram to be moved relatively to said carriage upon the engagement of said carriage with an abutment during traversing to transfer from said carriage to the anvil the upsettable member thereon, and means for resiliently holding on said carriage the upsettable member fed thereto.

6. A rivet carrier for transferring upsettable members fed thereto from a source to an anvil, comprising a housing, a carriage, means to feed upsettable members one at a time to said carriage, a stop member at one side of said carriage for positioning upsettable members as they are fed onto said carriage, said stop member being adjustable toward and away from said carriage, and being slidable in said housing, means to fix the adjustment of said stop member, said stop having a substantially flat face inclined to each direction of movement of said upsettable member for limiting movement of each upsettable member as it is fed onto said carriage, and for restraining movement of each upsettable member against said stop from movement from said carriage, a ram for transferring each upsettable member on said carriage to the anvil, means to traverse said ram and carriage toward the anvil and to return the same therefrom, said ram being movable from and into said housing as it is traversed, yieldable means for maintaining said carriage and ram in a predetermined relation for permitting said ram to be moved relatively to said carriage upon the engagement of said carriage with an abutment during traversing, to transfer from said carriage to the anvil the upsettable member thereon, and means for resiliently holding on said carriage the upsettable member fed thereto.
